UNITED STATES PATENT OFFICE.

HARRY THOMAS RANDOLPH, OF KANSAS CITY, KANSAS.

COVER.

1,330,345.

Specification of Letters Patent.

Patented Feb. 10, 1920.

Application filed June 14, 1919. Serial No. 304,213.

To all whom it may concern:

Be it known that I, HARRY THOMAS RANDOLPH, a citizen of the United States, residing at Kansas City, in the county of Wyandotte and State of Kansas, have invented certain new and useful Improvements in Covers, of which the following is a specification, reference being had to the accompanying drawings.

10 This invention relates to certain improvements in covers and has relation more particularly to a device of this general character especially designed and adapted for use in connection with laundry baskets and kindred receptacles, and it is an object of the invention to provide a novel and improved cover of this general character which may be readily and conveniently applied to the basket or receptacle and effectively maintained thereon.

15 It is also an object of the invention to provide a novel and improved device of this general character formed of flexible or pliable material whereby the same may be readily folded or compacted to occupy a minimum of space when not in use.

20 Another object of the invention is to provide a novel and improved device of this general character provided with particularly arranged fastening means whereby the cover may be effectively engaged with a basket to snugly engage the contents thereof when the occasions of practice may require in order to hold said contents against displacement.

25 The invention consists in the details of construction and in the combination and arrangement of the several parts of my improved cover whereby certain important advantages are attained and the device rendered simpler, less expensive and otherwise more convenient and advantageous for use, as will be hereinafter more fully set forth.

30 The novel features of my invention will hereinafter be definitely claimed.

35 In order that my invention may be the better understood, I will now proceed to describe the same with reference to the accompanying drawings, wherein:

40 Figure 1 is a view in perspective of a cover constructed in accordance with an embodiment of my invention and in applied position, the coacting basket being indicated by dotted lines and the opening in an end portion of the flap or skirt being also indicated by dotted lines, and

Fig. 2 is a fragmentary view in perspective of an end portion of my improved cover illustrating in detail the connection of the flexible member or strap 4.

60

My improved cover, as herein embodied, comprises a flexible or pliable sheet 1 of textile material, preferably duck, and which has its marginal portions defined by a continuous skirt or flap 2 adapted to overlie the sides of the basket or other receptacle when in applied position.

45 The skirt or flap 2 at each end of the sheet 1 is provided with a series of vertically disposed slots 3. The slots 3 extend in a direction transversely of the sheet 1 and are adapted to have disposed therethrough a handle as generally provided at each end of a laundry basket or kindred receptacle.

70

50 Secured to the inner face of each end portion of the skirt or flap 2 and at a point above the uppermost slot 3 is an end portion of a flexible member or strap 4 which is adapted to be disposed through the adjacent handle and extended upwardly and adjustably engaged with a buckle 5 secured to the outer face of the sheet 1 in close proximity to the adjacent end thereof. By this means, effective anchoring of the end portions of the cover to the basket or other receptacle 55 is obtained.

75

55 By having a series of vertically disposed slots 3, provision is made for the requisite coaction with a handle in accordance with the size of the load within the basket as in 60 packing laundry in a receptacle of this type, the load or contents generally extend above the upper or open face thereof.

80

65 Each side portion of the skirt or flap 2 adjacent its upper and lower margins is provided with coacting buckles 6 and coacting straps 7. Each coacting buckle and strap is in longitudinal alinement and operates whereby the skirt or flap 2 may be contracted to effect a snug and effective engagement of said skirt or flap 2 with the side walls of the basket or receptacle.

85

70 Secured to the outer face of the sheet 1, at the central portion thereof, is a pair of transversely alined buckles 8 positioned adjacent the side marginal portions of said sheet, and secured to the outer face of the sheet 1 and in substantially longitudinal alinement with each of the buckles 8 is an end portion of a strap 9. The strap 9 is 75 adjustably engaged with its alined buckle 8 whereby means are provided for contract-

105

110

ing the cover longitudinally as the occasions of practice may require and in order to assure a snug fitting of the cover over the basket or other receptacle and the load or 5 contents therein.

From the foregoing description, it is thought to be obvious that a cover constructed in accordance with my invention is particularly well adapted for use by reason 10 of the convenience and facility with which it may be assembled and operated, and it will also be obvious that my invention is susceptible of some change and modification without departing from the principles and 15 spirit thereof and for this reason I do not wish to be understood as limiting myself to the precise arrangement and formation of the several parts herein shown in carrying out my invention in practice except as 20 hereinafter claimed.

I claim:

1. A cover of the class described comprising a sheet of flexible material, a skirt secured to the marginal portions of said sheet, 25 longitudinally disposed straps arranged at the side marginal portions of the sheet, each

of the straps being anchored at one end portion to the sheet, and a holding member for the free end portion of each of the straps and secured to the sheet at a point substantially in longitudinal alinement with the connected end portion of the strap. 30

2. A cover of the class described comprising a sheet of flexible material, a skirt secured to the marginal portions of said sheet, 35 longitudinally disposed straps arranged at the side marginal portions of the sheet, each of the straps being anchored at one end portion to the sheet, and a holding member for the free end portion of each of the straps 40 and secured to the sheet at a point substantially in longitudinal alinement with the connected end portion of the strap, a pair of transversely separated straps secured to the longitudinal portions of the skirt, said 45 straps extending longitudinally of the cover, and holding members secured to each of the longitudinal portions of the skirt for coaction with said last named straps.

In testimony whereof I hereunto affix my 50 signature.

HARRY THOMAS RANDOLPH.
